UNITED STATES PATENT OFFICE.

CHARLES AXEL DAHL, OF LYNN, MASSACHUSETTS, ASSIGNOR TO THE GLOBE
BUTTONHOLE MACHINE COMPANY, OF KITTERY, MAINE.

BUTTON-HOLE STITCHING AND BARRING MACHINE.

SPECIFICATION forming part of Letters Patent No. 469,008, dated February 16, 1892.

Application filed January 9, 1891. Serial No. 377,230. (No model.)

To all whom it may concern:

Be it known that I, CHARLES AXEL DAHL, a subject of Oscar II, King of Sweden, now residing in Lynn, in the county of Essex and State of Massachusetts, have invented a new and useful Improvement in Button - Hole Stitching and Barring Machines, of which the following is a full, clear, and exact description, reference being had to the accompanying drawings, forming a part of this specification, in explaining its nature.

The invention relates, especially, to the work-clamps and clamp-plate; and it is to be used in lieu of the clamp-plate and clamps described in the Patents No. 450,844 and No. 450,950, dated April 21, 1891, and to be operated by mechanism described in the last patent, No. 450,950.

Referring to the drawings, Figure 1 is a view in perspective of a clamp-plate and work-clamps having the features of my invention. Fig. 2 is a view in perspective of the said clamp-plate and work-clamps inverted. Fig. 3 is a plan view thereof, showing its relation to the traveling and transfer-plates. Fig. 4 is a vertical section upon the dotted line $x-x$ of Fig. 3. Fig. 6 illustrates in section a modified form of the invention. Fig. 5 is a cross-section upon the dotted line $y-y$ of Fig. 3. Fig. 7 is a view to illustrate the relation between my improved clamp-plate and work-clamps and the operative devices described in said Letters Patent No. 450,950. Fig. 8 is a view, part in elevation, of the mechanism shown in Fig. 7; and Fig. 9 is a view, partly in cross vertical section and partly in elevation, to illustrate the connection between the work-clamps and the barring mechanism described in said Patent No. 450,950.

I have shown only such parts of my improved button-hole stitching and barring machine as are necessary to properly connect them with the new work-clamps and clamp-plate.

A is the bed of the machine, prepared as a slideway for the slide-plate A', which has intermittent periods of movement and rest communicated to it therein by a cam, as described in the said Patent No. 450,950. Upon the feed-plate A' is mounted the traversing plate A². This is attached to the feed-plate A' and

is operated by a cam, as described in the said last-named patent, and it carries or supports the clamp-plate B and work-clamps. The clamp-plate, instead of being made in two parts, which are separable upon the plate A², is in one piece—that is, it is not separable. It is secured at its front end to said plate A² by a central pivot b'. It has in its rear end the long recess b². It has also the rearwardly-extending arms b³, to which are pivoted to move laterally or transversely of the plate the work-clamps C C'. Each of these work-clamps comprises a block c, to the under surface of which extends forward a plate c', having upon its inner edge the inclined or wedge surface c². This plate c' may extend to a point beneath the presser-foot, or it may end with the wedge.

To the upper surface of the block c there is attached a spring-plate c³, which carries at its forward end the presser-foot c⁴. The block c is connected by a pivot c⁵ to its holding-arm b³ to permit the presser-foot to have a lateral or transverse movement upon the clamp-plate. The extent of this movement is limited by a pin c⁶ in the clamp-plate, and the slot c⁷ in the arm c', into which the pin extends.

I have described one of the work-clamps. The other is substantially like it and does not need further description, excepting as hereinafter indicated. They are moved and held toward each other by springs. There is one for each of the blocks c, and it is represented in one case or with one block as a flat spring h, fastened at its rear end to the side of the block and having an extension h' at its front end, which bears against the edge of the plate along the recess b². The work-clamp C' has additionally the arm D. This arm extends through the recess d in the plate B and connects with the plate c'. It extends upon the under side of the plate B to a position to be operated by the barring lever or arm E, which is like the lever F, described in the said last-named patent and need not further be described here. The extent of lateral movement of this clamp-plate C' and its arms is not limited by a pin and slot. It has a greater range of movement than that of the presser-foot C. This is for the purpose

of allowing it to be moved preparatory to barring the button-hole. A spring d' attached to the plate and to the arm D , acting in both directions, maintains the presser-foot 5 in proper operative position in relation to the other clamp-plate C . In use the material is placed beneath the presser-foot c^4 , and upon the starting of the machine the clamp-plate is moved with the material to bring it over 10 the anvil and beneath the button-hole cutter. This movement of the clamp-plate and clamps is like that described in the said Patent No. 450,950. The clamps are closed upon the work and spread at the beginning, and during this movement, as described in said patent, and by the same mechanism—namely, by means of a push-bar c^{16} , having a wedge-shaped front end c^{17} and a rear upward extension c^{18} , which extends into the path of 15 the cam c^{15} upon the shaft C^2 , (see Figs. 7 and 8,) so that the rotation of the cam causes the bar to be moved forward to separate the two members of the work-clamp by coming into contact with the wedge or inclined surfaces 20 thereon immediately after the operation of the cutter in cutting the button-hole.

The clamp-plate is held locked upon the plate A^2 in any desired position by means of the block F , which has a section f , entering a 30 notch f' in the end of the plate, and which also has a slot f^2 , through which a screw-stud f^3 passes. This stud, slot, and the nut f^4 serve to adjust the block upon the plate in any desired position. As the clamp is pivoted at b' to be moved or swung laterally, it follows that by moving the adjusting-block F laterally upon the plate A^2 that the clamp-plate and clamps are simultaneously adjusted or moved and their transverse position varied 35 relatively to the cutter and anvil.

It is not always necessary to use the arms c' between the presser-foot and the work-plate.

In Fig. 6 I have illustrated a slight modification in the method of supporting the arms 45 c^3 , and I have also shown therein the plates c' , integral with the block c , instead of being made separate therefrom. The arms c^3 , instead of being fastened to the upper surface of the blocks c , are represented as pivoted at 50 their heels g (see Fig. 6) to said blocks, one only of said arms and said blocks being shown. The block is also represented as having a hole g' for holding a coil-spring g^2 , which acts 55 against the under surface of the clamp-arm c^3 to move it upward and hold it in its elevated position. The wedge c^3 is formed upon the side of the block instead of the arm c' , and is thus thicker and has, therefore, greater wear.

60 Having thus fully described my invention, I claim and desire to secure by Letters Patent of the United States—

1. In a button-hole-stitching machine, the combination of the feed-plate A' , having feed movements, substantially as specified, imparted to it, with the clamp-plate B , attached 65 to said feed-plate to be movable with it and

having the long recess b^2 extending from the rear end of the plate forward, and the transversely-movable clamps $C C'$, carried by said clamp-plate B , as and for the purposes described. 70

2. The combination of the feed-plate A' , having feed movements of the character specified imparted to it, the clamp-plate B , attached to said feed-plate to be moved therewith and having the long recess b^2 extending from its rear end forward, and the clamps $C C'$, each of which comprises a block c , pivoted to the clamp-plate by a vertical pivot to swing or be 75 turned laterally, and an arm c' , having an operative wedge c^2 upon its inner surface attached to said block c , and a spring-arm c^3 , also attached to said block and carrying at its forward end a presser-foot c^4 over the forward part of the arm c' , and a spring for maintaining the said arms $c' c^3$ in position, as 80 and for the purpose described.

3. The combination of the feed-plate A' , the clamp-plate B in one piece attached to 85 said feed-plate to be moved therewith, the clamp C , pivoted at its rear end to the said clamp-plate to be movable laterally thereon, a stop for limiting the extent of said lateral movement, a spring for holding and maintaining it in a given position, and the clamp C' , pivoted at its rear end to the said clamp-plate to be movable laterally thereon, a spring 90 for maintaining it in a given position in relation to the clamp-plate and to the clamp C , and an arm connected with the clamp C' , by which lateral movement is imparted to it and through it to the clamp C , as and for the purposes described. 95

4. The combination of the feed-plate A' , 100 having feed movements of the character specified imparted to it, and an inextensible clamp-plate in one piece pivoted at its front end to said feed-plate and adjustably secured to its rear end to the said feed-plate, the said 105 clamp having the long recess b^2 extending from its rear end forward, with the clamps $C C'$, pivoted to the clamp-plate to be movable transversely thereon in opposition to positioning-springs, and said positioning-springs, 110 substantially as described. 115

5. The combination of the feed-plate A' , the inextensible clamp-plate B , pivoted at its front end to said feed-plate A' , adjusting devices secured to the said feed-plate A' for adjusting the rear end of said clamp-plate, and the clamps $C C'$, pivoted to the clamp-plate B to be transversely movable thereon and adjustable simultaneously with the rear end thereof, as and for the purposes described. 120 125

6. The combination of the feed-plate A' , having feed movements, substantially as specified, imparted to it, the inextensible clamp-plate B , attached to the feed-plate to be movable with it and having the recess b^2 , and the 130 laterally-movable clamps $C C'$, carried by said clamp-plate B , and each of which has an under rest for supporting the material upon each side of the button-hole slit, and a presser-foot

to bear upon the upper surface of the material and clamp it against the under rest, as and for the purposes described.

7. The combination of the feed-plate A', having feed movements, substantially as specified, imparted to it, the inextensible clamp-plate B, having the recess b^2 extending from its rear edge, the stationary button-hole anvil and its co-operating cutter contained in said recess

b^2 , and the spreading-clamps C C', each of which comprises a lower plate or rest c' and an upper plate or presser-foot c^4 , and each of which has the wedge c^3 and the clamp-spreader c^{17} , substantially as described.

CHARLES AXEL DAHL.
